UNITED STATES PATENT OFFICE.

STEPHEN A. WALL, OF PATERSON, NEW JERSEY.

DESIGN FOR A SIGN-BOARD.

SPECIFICATION forming part of Design No. 24,348, dated May 28, 1895.

Application filed April 18, 1895. Serial No. 546,273. Term of patent 8½ years.

To all whom it may concern:

Be it known that I, STEPHEN A. WALL, a citizen of the United States, residing at Paterson, in the county of Passaic and State of New Jersey, have invented and produced a new and original design for sign-boards for attracting the attention of persons to the notices posted on the premises that are for sale or to let, of which the following is a specification, reference being had to the accompanying drawing, forming a part thereof.

The drawing represents a diagrammatical view of a sign-board, showing my design.

The leading feature of the design constitutes a rectangular outline with diagonal division line extending from corner to corner and a division line parallel with the edges

having star-like ornamentations with a star-like figure at each corner of the sign-board.

A is the sign board having a diagonal line B extending from diagonally opposite corners, and the ornamental division line C extending parallel with the edges of the notice and having star-like ornamentations as shown.

At each corner of the sign board are shown star-like ornamentations D.

What I claim is—

The design for a sign board, substantially as herein shown and described.

STEPHEN A. WALL.
